UNITED STATES PATENT OFFICE.

ADIEL Y. DODGE, OF RACINE, AND ROBERT J. STATZ, OF WIND POINT, RACINE, WISCONSIN, ASSIGNORS TO FREEMAN MANUFACTURING COMPANY, OF RACINE, WISCONSIN, A CORPORATION OF WISCONSIN.

TURNTABLE.

Application filed April 5, 1923. Serial No. 629,984.

To all whom it may concern:

Be it known that we, ADIEL Y. Dodge and ROBERT J. STATZ, citizens of the United States, residing at Racine, in the county of Racine and State of Wisconsin, and Wind Point, Racine, in the county of Racine and State of Wisconsin, respectively, have invented new and useful Improvements in Turntables, of which the following is a full, clear, concise, and exact description, reference being had to the accompanying drawing, forming a part of this specification.

Our invention relates to turntables, and more particularly to portable turntables for turning loaded trucks. Such a turntable is useful for instance in building roads, where the material to be used is hauled in trucks on the sub-grade and is dumped near the place where it is to be used. It might be difficult and sometimes impossible to turn the truck around on the sub-grade on its own wheels, due to the narrow width of the sub-grade and the fact that ditches might be at the sides of the sub-grade, so portable turntables are being used, located near the place where the material is to be used, onto which the truck can be run and on which it can be turned around so that it can back up to the place where the material is to be used and there dumped.

When the road building progresses up to or near the turntable, the turntable is then dragged ahead some distance, so as to allow the road building to progress.

One of the objects of our invention is to provide an improved turntable which will be what we term "self-balancing", and "self-lifting"; self-balancing in that when the truck is driven onto the runway, the truck will be automatically balanced so that the center of gravity will be close to the axis of rotation of the turntable, and "self-lifting", in that when the table tilts to a self-balancing position, the approach end of the runways will be swung up high enough so as to clear the forms at the side of the road or other obstructions.

A further object of our invention is to provide a turntable which will be very easy to operate, so that one man can easily turn it under any conditions.

A further object of our invention is to

provide improved means for lubricating the anti-friction supports for the table.

A further object of our invention is to provide a turntable which is so designed that it will be very light, thereby cutting the cost of construction and making for ease of operation.

Further objects will appear from the detailed description to follow and from the appended claims.

In the drawings in which two forms of our invention are shown—

Figure 1 is a plan view of a turntable embodying our invention;

Fig. 2 is a side view of the turntable showing the approach end resting on the roadway;

Fig. 3 is a section on the line 3—3 of Fig. 1;

Fig. 4 is a side view of a latch construction;

Fig. 5 is a plan view showing a lighter, cheaper form of turntable embodying our invention;

Fig. 6 is a side elevation of the turntable shown in Fig. 5; and

Fig. 7 is a section on the line 7—7 of Fig. 5.

Referring now to the drawings in detail, and first to Figs. 1, 2 and 3 and 4, the construction shown comprises a slideable base, in the nature of a skid or scow, which can be dragged from place to place, and a bridge member comprising a pair of spaced runways, mounted on said slideable base for rotation about a vertical axis, and also tiltably mounted to permit the approach end of the runway to be brought down on the roadway for the truck to be driven up on the bridge.

The bridge is tiltably mounted on a fulcrum member, which fulcrum member is located near the axis of rotation of the turntable, so that as the truck is driven up onto the bridge, the bridge will tilt, and move to horizontal position, at the moment that the center of gravity of the truck passes the axis of the fulcrum, the approach end of the bridge being thus lifted from the roadway, and being raised high enough so that when the table is turned, the end of the bridge will clear the forms at the side of the roadway or other obstructions.

A stop member is provided in order to prevent the bridge from tipping too far when the center of gravity of the truck passes the axis of the fulcrum, and an additional auxiliary stop member is provided, mounted on the bridge itself, which will engage the roadway, to stop the tilting movement of the bridge in case the primary stop member fails to stop the tilting movement of the bridge.

The rotatable and tiltable bridge member comprises a pair of spaced runways 10, of substantially channel cross section, as shown in Fig. 3, these runways 10 being united by cross pieces 11, which extend between and underneath the runways 10. The bridge is tiltably mounted on a transversely extending fulcrum member 12, which extends underneath the runways 10, and a transversely extending stop member 13, similar in construction to the fulcrum member 12, is provided to limit the tipping movement of the runway when the center of gravity of the load passes the axis of the fulcrum member 12.

Both the fulcrum member 12 and the stop member 13 are mounted for rotation together about a vertical axis along with the bridge, the fulcrum member and the stop member being mounted on a rotatable dished member 14, which forms the main rotatable support for the fulcrum member, the stop member, and the bridge. This dished member 14 is rotatably mounted in an outer dished member 15, a circularly arranged anti-friction device being provided between the inner and outer dished members, as indicated at 16, the dished members being provided with ball races to receive the balls 17 of the anti-friction device.

The shape of the dished members 14 and 15, which is similar to that of a tank head, is such that they are well adapted to resist the stresses to which they are subjected, the deep upwardly extending flanges providing great strength and rigidity at the places where these are required.

The space between the inner and outer dished members is used as an oil reservoir so that the balls operate in an oil bath.

The outer dished member 15 is mounted on the slidable base 18. A central axial anti-friction bearing is provided to take care of the greater portion of the weight of the turntable and truck mounted thereon, in the form of a vertical thrust bearing as indicated at 19. As indicated in Figs. 1 and 3, the fulcrum member 12 and the stop member 13 are each supported at three points, as indicated at 20, 21 and 22. The two points of support 20 and 21 are on the rim or upwardly extending flange of the inner rotatable dished member 14, while the central point of support 22 is on the two beam members 23 which carry the load down to the thrust bearing 19.

As intimated above, when the truck is driven onto the runway, and the center of gravity of the load passes the axis of the fulcrum member 12, the runway tips to horizontal position, and the driver thereupon immediately throws out his clutch and puts on his brakes, bringing the truck to a stop within a foot or so, so that the center of gravity of the load is very near the center of rotation of the turntable. This brings probably 80% of the weight of the load on the central axial thrust bearing at 19. The driver can tell immediately when the bridge begins to tip, as he can feel it move, see it tipping, and hear the click when the bridge strikes the stop member 13.

In order to prevent foreign substances, such as dust and the like, from getting into the oil bath between the dished members 14 and 15, dirt excluding means are provided, comprising an annular felt member 24 secured to a downwardly extending annular skirt member 25 which in turn is secured by means of clips 26 to an annular angle member 27, riveted to the upwardly extending flange 28 of the inner rotatable dished member 14.

It will be noted that the annular felt piece 24 engages a flat surface, so that there is no tendency for the felt to bind or wrap about the rotatable member, as might be the case if the felt member engaged a cylindrical surface.

The central portion of the outer dished member 15 rests on a heavy plate 29 secured to the bottom of the slidable base 18, while the outer portion of the dished member 15 is supported by an annular angle member 30, having one flange secured to the dished member as indicated at 31, and the other flange secured to the bottom of the slidable base as indicated at 32.

Oil is supplied to the space between the inner and outer dished members through a supply pipe 33 screwed into the inner dished member, the supply pipe being provided with a screw plug 34 for closing the filling opening.

The two dished members 14 and 15 may be pressed from sheet metal. The slidable base may be formed of plates and structural shapes. The beams 23 which support the balancing portion of the load may be I-beams. The cross pieces 11 may be structural or pressed shapes. The runways 10 as shown in Fig. 3 comprise the plate 35 on which the truck wheels 36 rest, the inner angle member 37, to assist in taking care of the bending strains and to form an inner guide flange, and a deep built-up outer flange member, formed of two angle sections 38 and 39, to take care of the main bending stresses, and to form an outer guide flange. It will be noted that the inner flange 37 is comparatively shallow so that there is am-

ple clearance for the brake drum 40, while the outer flange is considerably deeper, in order to take care of the heavy bending stresses. The cross pieces 11 carry the stress

5 due to the pressure of the truck wheels from the plate 35 and the inner shallow flange 37 out to the outer deep flange, which is of ample section to take care of the bending stress.

10 The central axial thrust bearing 19 comprises a journal member 41 secured to the fixed outer dished member 15 by means of bolts 42, this journal member having an annular flange portion held between the upper 15 and lower plates 43 and 44 which are secured to the inner rotatable dished member 14 by means of bolts 45.

The auxiliary stop for limiting the tipping of the bridge in case the main stop 20 member 13 fails to stop the tilting movement, comprises a pivoted foot member 46, pivoted to the end of the bridge at 47, and operated by means of a hand lever 48. This hand lever 48 may also be used for swinging 25 the bridge about its vertical axis.

In turning the table, after the truck has been driven onto it, the lever 48 is swung as indicated in the direction of the arrow A, to fold the pivoted foot 46 up into line with 30 the bridge which leaves the hand lever 48 extending outwardly into a position convenient for use in swinging the table around. This pivoted foot 46 is intended for use only as an auxiliary or emergency stop, in case the 35 truck should run so far forward as to cause the bridge to tip downwardly about the stop member 13 as a fulcrum, or if for any other reason the main stop member 13 should fail to stop the bridge in its tipping movement.

40 When a truck is about ready to run up onto the bridge, an operator takes hold of the far end of the bridge and lifts up on it, to bring the approach end of the bridge down onto the roadway as shown in Fig. 2 so 45 that the truck can run up onto it. In order that the operator may not have to hold up on the bridge after he has tilted it up, a yielding latch device is provided (Figs. 2 and 4). This yielding latching device comprises a reciprocable latch or cam member 49, having an inclined portion 50 which engages the upper edge of the stop member 13, a coil compression spring 51 being provided, surrounding this latch member and thrusting it with sufficient force against the fulcrum member, to hold the bridge in its up-tilted position. One end of the latch member 50 is carried by a swinging link 52, the other end being slidable in a bracket 53 secured to 55 the bridge. The inclination of the edge 50 of the latch member which engages the stop member 13 is so arranged and the spring 51 is so designed that this latch member will yield as soon as the center of gravity of the 60 truck passes the fulcrum member 12 to per-

mit the bridge to tilt into horizontal position.

In moving the turntable from place to place, it may either be dragged supported by the skid or slid able base 18, which is turned 70 up at both ends as indicated at 54 and 55 to facilitate this operation, or one end of the turntable may be supported on a trailer, and the other end on the rear end of one of the trucks, and the turntable hauled along behind the truck. 75

In order to facilitate this latter operation, means are provided whereby when the bridge is picked up, and supported between the trailer and the truck, the skid or slid able 80 base also will be picked up along with the bridge and supported underneath the bridge. This construction, as shown in detail in Fig. 3, comprises a heavy bolt at 56, heavy enough to support the weight of the skid or slid able 85 base at the dished members 13 and 14 and associated parts, this bolt being loosely connected at one end to the I-beam 23 and loosely connected at the other end to one of the cross pieces 11. 90

This loose connection of the bolt 56 and parts connected thereby permits the necessary tilting of the bridge. In order to take up some of the slackness of this connection when the bolt 56 is used as a support in carrying the parts suspended underneath, a latch member or plate 57 is provided, which when the turntable is in use, is turned to lie in the channel portion of the cross piece 11, and when the turntable is being carried from 95 one place to another as above described, it is turned to bring the ends of the latch member 57 to rest on the oppositely disposed flanges of the cross piece 11. 100

The use and operation of the turntable has 105 been outlined in connection with the description of the construction. Briefly, the turntable is set up at one side of the sub-grade, near the place where the material is to be dumped. As a loaded truck approaches, the 110 bridge is swung around so as to extend longitudinally of the roadway, and the attendant tips up the far end of the bridge, which is the end provided with the pivoted foot 46, until the other end of the bridge, which is 115 the approach end, rests on the sub-grade. The bridge will be held in tilted position by means of the latch 49. The driver of the truck then drives his truck up onto the bridge. When the center of gravity of the 120 loaded truck passes the axis of the fulcrum member 12, the bridge and the truck will tilt about this fulcrum, the latch 49 yielding readily to permit this tilting. The moment the bridge and the truck begin to tilt, the 125 driver of the truck throws out the clutch and throws on the brakes and brings the truck to a stop on the bridge in a short distance, probably a foot or so. As the axis of the fulcrum member 12 is about a foot from the 130

axis of rotation of the bridge, the center of gravity of the load will be brought to rest approximately over the vertical axis of rotation of the bridge, and therefore substantially over the main thrust bearing at 19, so that the main portion of the load will be carried by this main thrust bearing at 19. The bridge is stopped in its tilting movement and held in horizontal position by means of 10 the stop member 13, which is located about a foot from the far side of the vertical axis of rotation of the bridge, and about 2 feet from the fulcrum member 12. The bridge and the truck are thus supported about 15 equally by the fulcrum member 12 and the stop member 13.

In case the brakes should fail to work, or if for any reason the truck should overrun until the center of gravity passes the stop 20 member 49, the emergency or auxiliary stop or pivoted foot 46 will hold the bridge in substantially horizontal position by its engagement with the roadway.

This foot 46 will also stop the tilting 25 movement of the bridge in case the momentum of the bridge and truck should be so great that the bridge would continue to tilt even after it had engaged the stop member 13.

After the truck and bridge have been balanced on the fulcrum member 12 and stop member 13, the attendant takes hold of the lever 48, and swings in the direction indicated by the arrow A in Fig. 2 to fold the 30 foot 46 up out of the way and bring the lever 48 out into position convenient for swinging the bridge about its vertical axis.

The attendant then swings the bridge about its vertical axis by means of the lever 35 or push bar 48, swinging the bridge through substantially 180 degrees, and thus turning the truck end for end.

The driver of the truck now backs the truck off. In this backing off movement, the 40 bridge will begin to tilt as soon as the center of gravity passes the fulcrum member 12, and this tilting movement will continue until the end of the bridge which has been referred to as the approach end rests on the 45 ground, thus permitting the truck to be readily backed down off the bridge without much jolting.

The driver then continues to back up the truck until it is where the material is to be 50 dumped. After dumping the truck, the driver is all ready to start off for another load. As the bridge extends longitudinally of the roadway, there is ample room for the truck to pass it without getting off the sub-grade.

Suitable means are provided for preventing 55 the bridge from sliding endwise on the fulcrum and stop members, and from slipping off sidewise. For this purpose, clips 60 58 are secured to the under side of the run-

way 10 and the flanges of the fulcrum and stop members are cut away as indicated at 59, for cooperation with these clips 58. Endwise movement of the bridge is prevented by the engagement of the clip 58 with the web 70 portion of the channel member forming part of the stop member and fulcrum member, and lateral movement of the bridge is prevented by the engagement of the edge of the clip 58 with the cutaway edge of the flange 75 portion of the said channels.

Referring now to Figs. 5, 6 and 7, the construction shown therein is lighter and cheaper than that previously described. The runway may be similar to the one previously 80 described, and also the slidable base or skid. In this construction, the inner and outer dished members and ball race are dispensed with and the fulcrum member 60 and the stop member 61 are supported for rotation 85 together on a vertical post 62 which is suitably supported on the slidable base or skid 63.

The fulcrum member 60 and the stop member 61 are suspended from a rotatable 90 head 64 by means of four angle clips 65. This rotatable head 64 is rotatable on the upwardly extending pin or post 62. The vertical pin 62 and the rotatable head 64 are supported on a stationary head 66 which 95 is secured to the slidable skid or base 63. Any suitable means, not necessary to be described in detail, may be provided for holding the runways against lateral or longitudinal sliding on the fulcrum member 60 and 100 the stop member 61. These means may be similar to those disclosed in connection with the form previously described, or any other suitable means may be provided. The bridge in this form may be provided with a pivoted 105 foot 67 and hand lever 68 just as in the form previously described. The use and operation of this bridge is substantially the same as in the form previously described.

While we have shown but two forms of 110 our invention, it is obvious that it may be embodied in other forms covered and defined by the appended claims.

Having thus described our invention, what we claim as new and desire to secure 115 by United States Letters Patent is:

1. A portable turntable comprising a base 120 slidable on the roadway, a fulcrum member and a stop member spaced from said fulcrum member, said fulcrum member and said stop member both being mounted on said slidable base and rotatable together about a vertical axis, and a runway for a truck tiltably mounted on said fulcrum, and tiltable from a position in which one end of the runway is low enough for the truck to drive onto the runway, to a position in which the runway engages the stop member and is held in substantially horizontal position, whereby when the truck is driven onto 125 130 the runway is high enough to clear the stop member.

- the runway, the runway will automatically tilt to a horizontal position in which it is held by said stop member, when the center of gravity of the truck passes the fulcrum member.
2. A portable turntable comprising a base 5
slidable on the roadway, a fulcrum member, a stop member, spaced from said fulcrum member, both said fulcrum member and said stop member being mounted on said 10
slidable base and rotatable together about a vertical axis, and a runway for a truck tiltably mounted on said fulcrum, and tiltable from a position in which the approach end of the 15
runway is low enough for the truck to drive thereon, to a substantially horizontal position, in which the runway engages said stop member, and an auxiliary stop member mounted on said runway at the end opposite 20
the approach end, for engaging the roadway to limit the tilting movement of the runway in case the stop member fails to stop the tilting movement.
3. A portable turntable comprising a base 25
slidable on the roadway, a fulcrum member, a stop member, spaced from said fulcrum member, both said fulcrum member and said stop member being mounted on said 30
slidable base and rotatable together about a vertical axis, and a runway for a truck tiltably mounted on said fulcrum, and tiltable from a position in which the approach end of the runway is low enough for the truck to drive thereon, to a substantially 35
horizontal position, in which the runway engages said stop member, and an auxiliary stop member mounted on said runway at the end opposite the approach end, for engaging the roadway to limit the tilting movement of the runway in case the stop member fails to stop the tilting movement, said auxiliary stop being pivotally mounted on the runway to fold out of the way when the runway is being rotated.
4. A portable turntable comprising a base 45
slidable on the roadway, a circularly arranged anti-friction device mounted on said 50
slidable base, a fulcrum member, a stop member spaced from said fulcrum member, said fulcrum member and stop member being supported for rotation together about a vertical axis by said anti-friction device, and a runway for a truck tiltably mounted on said fulcrum, and tiltable from a position 55
in which the approach end of the runway is low enough for a truck to drive thereon, to a substantially horizontal position in which it engages said stop member, whereby as the truck is driven onto the runway, the runway will automatically tilt to a horizontal position in which it is held by said stop member when the center of gravity of the truck passes the fulcrum member, and means for holding the approach end of the runway in 60
lowered position when tilted by the attendant for the truck to drive thereon, whereby the attendant does not have to hold up the other end of the runway after he has tilted it up.
7. A portable turntable comprising a base 65
slidable on the roadway, a fulcrum member, a stop member spaced from said fulcrum member, said fulcrum member and stop member both being mounted on said 70
slidable base for rotation together about a vertical axis, a runway for a truck tiltably mounted on said fulcrum member, and tiltable from a position in which the approach end of the runway is low enough for the truck to 75

drive thereon, to a substantially horizontal position in which it is held by said stop member, whereby as the truck is driven over the runway, the runway will automatically tilt to a horizontal position in which it is held by said stop member when the center of gravity of the truck passes the fulcrum member, and automatic means for holding the approach end of the runway in lowered position when tilted by the attendant for the truck to drive thereon, whereby the attendant does not have to hold up the other end of the runway after he has tilted it up.

8. A portable turntable comprising a base 15 slidable on the roadway, a fulcrum member, a stop member spaced from said fulcrum member, said fulcrum member and stop member both being mounted on said slidable base for rotation together about a vertical 20 axis, a runway for a truck tiltably mounted on said fulcrum member, and tiltable from a position in which the approach end of the runway is low enough for the truck to drive thereon, to a substantially horizontal position 25 in which it is held by said stop member, whereby as the truck is driven over the runway, the runway will automatically tilt to a horizontal position in which it is held by said stop member when the center of 30 gravity of the truck passes the fulcrum member, and spring means for holding the approach end of the runway in lowered position when tilted by the attendant for the truck to drive thereon, whereby the attendant 35 does not have to hold up the other end of the runway after he has tilted it up.

9. A portable turntable comprising a base 40 slidable on the roadway, a fulcrum member, a stop member spaced from said fulcrum member, said fulcrum member and stop member both being mounted on said slidable base for rotation together about a vertical axis, a runway for a truck tiltably mounted on said fulcrum member, and tiltable from a position in 45 which the approach end of the runway is low enough for the truck to drive thereon, to a substantially horizontal position in which it is held by said stop member, whereby as the truck is driven over the runway, the runway will automatically tilt to a horizontal position in which it is held by said stop member when the center of gravity of the truck passes the fulcrum member, and yielding means for holding the approach 50 end of the runway in lowered position when tilted by the attendant for the truck to drive thereon, whereby the holding means will yield to permit the runway to tilt to horizontal position when the center of gravity 55 of the truck passes the fulcrum member.

10. A portable turntable comprising a base 60 slidable on a roadway, a fulcrum member, a stop member spaced from said fulcrum member, said fulcrum member and stop member being mounted on said slid-

able base for rotation together about a vertical axis, a runway for a truck tiltably mounted on said fulcrum member and tiltable from a position in which the approach end of the runway is low enough for the truck to drive thereon to a horizontal position in which it is held by said stop member, whereby if the truck is driven onto the runway, the runway will automatically tilt to a horizontal position in which it is held by said stop member, when the center of gravity of the truck passes the fulcrum member, and anti-friction means for supporting said runway, comprising axially located central anti-friction device for supporting the balanced portion of the load, and a circularly arranged anti-friction device coaxial with said central friction device, for supporting the unbalanced portion of the load.

11. A portable turntable comprising a base slidable on the roadway, and a bridge member for supporting a truck mounted on said slidable base for rotation about a vertical axis, said bridge member comprising a pair of spaced runways, one on each side of said bridge, for supporting the wheels of the truck, and cross members extending between and underneath said runways, said runways being of channelled cross sections, the inner flange of the channel section being lower than the brake drum of the truck to provide clearance, and the outer flange of the channel being considerably higher than the inner flange, to provide strength to resist bending, said cross member serving to carry the load from the horizontal web portion of the channel and from the inner flange of the channel to the strong outer flange of the channel.

12. A portable turntable comprising a base slidable on the roadway, a runway for a truck mounted on said slidable base for rotation about a vertical axis, and anti-friction means for supporting said runway for rotation, comprising an outer circular dished member having a peripheral strengthening flange mounted on said slidable base, a circular inner dished member having a peripheral strengthening flange 115 within said outer dished member, and rotatable therein, on which said runway is mounted, and a circularly arranged anti-friction device between said dished members.

13. A portable turntable comprising a bridge slidable on the roadway, a runway for a truck mounted on said slidable base for rotation about a vertical axis, and anti-friction means for supporting said runway for rotation comprising an outer circular dished member having an upwardly extending peripheral strengthening flange, mounted on said slidable base, a circular inner dished member having an upwardly 125 extending peripheral strengthening flange, mounted on said slidable base, a circular inner dished member having an upwardly 130

extending peripheral strengthening flange, within said outer dished member and rotatable therein, on which said runway is mounted, a circularly arranged anti-friction device between said dished members, and means for supplying lubricant to the anti-friction device between said dished members.

14. A portable turntable comprising a bridge slidable on the roadway, a runway for a truck mounted on said slidable base for rotation about a vertical axis, and anti-friction means for supporting said runway for rotation comprising an outer circular dished member having an upwardly extending peripheral strengthening flange, mounted on said slidable base, a circular inner dished member having an upwardly extending peripheral strengthening flange, within said outer dished member and rotatable therein, on which said runway is mounted, a circularly arranged anti-friction device between said dished members, and means for supplying lubricant to the anti-friction device between said dished members, and means for preventing foreign substances from entering between the flanges of said dished members.

15. A portable turntable comprising a bridge slidable on the roadway, a runway for a truck mounted on said slidable base for rotation about a vertical axis, and anti-friction means for supporting said runway for rotation comprising an outer circular dished member having an upwardly extending peripheral strengthening flange, mounted on said slidable base, a circular inner dished member having an upwardly extending peripheral strengthening flange, within said outer dished member and rotatable

therein, on which said runway is mounted, a circularly arranged anti-friction device between said dished members, means for supplying lubricant to the anti-friction device between said dished members, and means for preventing foreign substances from entering between the flanges of said dished members, comprising an annular felt member engaging the upper edge of the flange of the outer dished member and mounted on the inner dished member.

16. A portable turntable comprising a base slidable on the roadway, a fulcrum member, a stop member spaced from said fulcrum member, a runway for a truck tiltably mounted on said fulcrum member and tiltable from a position in which the approach end of the runway is low enough for the truck to drive thereon to a substantially horizontal position in which it is held by said stop member, and anti-friction means for supporting said fulcrum member and said stop member for rotation about a substantially vertical axis comprising an outer circular dished member having an upwardly extending peripheral strengthening flange, mounted on said slidable base, a circular inner dished member having an upwardly extending peripheral strengthening flange, within said outer dished member and rotatable therein, on the flange of which said fulcrum member and stop member are mounted, and a circularly arranged anti-friction device between said dished members.

In witness whereof, we have hereunto subscribed our names.

ADIEL Y. DODGE.
ROBERT J. STATZ.
